ABSTRACT: A lockstitch sewing machine having an oscillating loop taker is provided with a mechanism for replenishing thread on the bobbin while the bobbin is in place in the loop taker and while the loop taker partakes of the same oscillatory movement as during stitch formation. Means are disclosed for introducing thread to the bobbin in place on the loop taker, and a ratchet device is driven by the oscillating loop taker driver for turning the bobbin in only one direction to wind the thread thereon.

BOBBIN THREAD REPLENISHING MECHANISMS FOR SEWING MACHINE WITH OSCILLATING SHUTTLE

BACKGROUND OF THE INVENTION

The technique of winding thread upon a bobbin in place in a rotary loop taker has been quite highly developed, and as disclosed in the U.S. Pat. No. 3,012,530, to Stanley J. Kettner et al. Dec. 12, 1961, to which reference may be had, the use of a rotating bobbin driving member in a rotary loop taker for bobbin thread replenishment is well known. Where the bobbin driving member and the loop taker drive each rotate, there need be no relative movement therebetween during sewing operations and therefore, exceedingly simple, friction-free mechanisms are possible. In an oscillating loop taker, however, prior known bobbin rotating devices, albeit theoretically plausible, would be highly impractical because of the complexity of construction and the bearing problems which would arise because of the relative motion which would exist during the long periods of sewing while the bobbin replenishing means is ineffective.

Heretofore, bobbin thread has been replenished successfully on a bobbin in place in an oscillating shuttle by a process as disclosed in the U.S. Pat. No. 3,096,736, to R. E. Johnson July 9, 1963 in which at each needle reciprocation, a fresh loop of needle thread is seized and cast onto the bobbin. In this patented construction bobbin thread replenishment results from the successively deposited thread loops rather than from a driven rotation of the bobbin.

BRIEF SUMMARY OF THIS INVENTION

In the present invention, bobbin thread is replenished on a bobbin in place in an oscillating loop taker by means of a ratchet drive for the bobbin by which the bobbin is rotated in increments during thread replenishment by a driver which oscillates with the loop taker driver. The same advantages of simplicity and absence of friction incident to relative motion of the bobbin and loop taker driver during sewing is, therefore, attained with the present invention as had heretofore been obtained with rotary loop takers. As compared with the prior known arrangement for replenishing bobbin thread in an oscillatory loop taker in which successive loops are cast onto the bobbin, the present invention is advantageous in that the replenishment thread may be directed through a bobbin thread tensioning spring and therefore, a greater uniformity of stitching can be obtained.

Another advantage of the construction of the present invention for replenishing bobbin thread in an oscillating loop taker sewing machine is that a more even winding of thread on the bobbin can be attained and consequently a greater quantity of thread can be replenished on the bobbin than an arrangement in which successive loops of thread are deposited.

DESCRIPTION OF THE DRAWINGS

With the above and additional objects and advantages in view as will hereinafter appear, this invention comprises the devices, combinations, and arrangements of parts hereinafter described and illustrated in the accompanying drawings of a preferred embodiment in which:

FIG. 1 represents a vertical cross-sectional view of a portion of a sewing machine work supporting bed showing an oscillating lockstitch forming loop taker together with a fragment of the oscillating drive therefor in vertical cross section and having a bobbin thread replenishing mechanism applied thereto in accordance with this invention and shown in the retracted or sewing mode.

FIG. 2 represents an enlarged vertical cross-sectional view of the bobbin case of FIG. 1 with a fragment of the loop taker and a fragment of the bobbin rotating member shown in effective position for influencing the bobbin replenishing mode.

FIG. 3 is an exploded perspective view of the loop taker, bobbin case bobbin, and of the parts associated therewith for winding replenishment thread on the bobbin,

FIG. 4 is a side elevational view of the bobbin case showing the needle thread being manually introduced thereto for initiation of bobbin thread replenishment,

FIG. 5 is a front elevational view of the bobbin case together with an oscillating shuttle showing the needle thread manually introduced for initiation of bobbin thread replenishment as in FIG. 4,

FIG. 6 represents a cross-sectional view of the bobbin case taken substantially along line 6-6 of FIG. 5 showing the relationship of the manually introduced needle thread to the bobbin flange upon initiation of bobbin thread replenishment, and

FIG. 7 represents a cross-sectional view taken substantially along line 7-7 of FIG. 4 showing the disposition of thread during the course of bobbin thread replenishment.

Referring to FIGS. 1, 2, 3, and 4 of the drawings, a work supporting bed of a sewing machine is indicated at 11 and is formed with a web 12 apertured at 13 to accommodate a bushing 14. Journaled in the bushing is a loop taker drive shaft 15 which is formed with or has secured thereto a shuttle driver 16 at one side of the bushing 14. A collar 17 secured by a setscrew 18 to the shaft 15 at the opposite side of the bushing locates the shaft axially in the machine bed.

Carried on the bed spanning a loop taker accommodating recess 20 therein is a throat plate 21 formed with a needle aperture 22 and with slots 23 through which extends a work transporting feed dog 24. Beneath the throat plate and within the loop taker accommodating recess 20 is arranged a shuttle housing 25 which may be secured by any conventional means 30 to the web 12 in the bed and which is formed with a bearing raceway 26 in which a shuttle 27 is journaled. A housing cap 28 which may be hinged as at 29 to the shuttle housing is formed with a bearing projection 30 complementary to the bearing raceway 26 in order to constrain the shuttle within the housing. A bearing rib 31 on the shuttle which is constrained between the raceway 26 and the bearing projection 30 is formed with a needle loop seizing beak 32 as is conventional and the shuttle is formed with a thread camming front skirt 33.

The shuttle driver 16 engages with and moves the shuttle 27 in an oscillatory fashion alternately over somewhat greater than one-half revolution increments in opposite directions as is well known in oscillatory shuttle lockstitch sewing machines. The shuttle 27 is formed with a central post 35 upon which is accommodated a bobbin case 36. A latch device 37 on the bobbin case may be moved into and out of gripping relation with an annular notch 38 formed on the extremity of the post 35 to maintain the bobbin case in the shuttle and a rotation restraining arm 39 on the bobbin case is embraced by a notch 40 formed in the shuttle housing cap 28 to prevent the bobbin case from oscillating with the shuttle.

The bobbin case 36 is formed with a central sleeve 41 which embraces the shuttle post 35 and on which sleeve a hub 42 of a thread carrying bobbin 43 is freely rotatable. Preferably the bobbin is formed with identical flanges 44. The bobbin case is also formed with a peripheral skirt 45 which surrounds the bobbin 43. The skirt is formed with a thread guiding slot 46 into which thread from the bobbin may be led when the bobbins are wound in conventional fashion while separated from the loop taker. A thread tensioning spring 47 secured to the skirt 45 as by a screw 48 overlies the mouth of the thread guiding slot 46 and frictionally opposes passage of thread from the bobbin.

The construction thus far described is conventional in the sewing machine art and it will be understood that although a specific form of conventional oscillating shuttle mechanism has been described, this invention as will now be described with relation thereto, may be applied with minor variation to any known oscillating lockstitch forming mechanisms.

Since in this invention, thread is to be wound on the bobbin in place in the loop taker, provision is necessary for introducing thread from a source outside the shuttle to the bobbin. To this end an auxiliary thread guiding slot 60 is formed in the bobbin case which, as shown particularly in FIGS. 4, 5, and 6, 75 extends from the face of the bobbin case to the skirt 45 and

terminates at 61 closely adjacent to the termination of the conventional thread guiding slot 46 so that the thread issuing from either slot 46 or 60 will be subjected to the tensioning effect of the spring 47. When the thread N from a conventional sewing needle, as shown in FIGS. 4, 5, and 6, is manually introduced to the slot 60, this thread will be directed over the edge of one of the bobbin flanges 44 as shown in FIG. 6.

Insofar as thread disposition is concerned, the needle thread N when placed and held as shown in FIGS. 4, 5, and 6, is in readiness to be wound on the bobbin. It is necessary that the thread guiding slot 60 be located so that in regular sewing operations the threads will not be directed into the slot 60.

The bobbin 43 in this invention is required to have two features which depart from conventional bobbin construction. First the periphery of each bobbin flange 44 must be formed with at least one radial slot 65. Although a single slot in each flange is sufficient, a plurality of radial slots 65 in each flange will increase the speed at which thread replenishment will begin. The slots 65 serve, when the thread is directed over the flange periphery, as shown in FIG. 6, to catch the thread loop and anchor the thread to the bobbin when the bobbin is rotated. The second departure from conventional bobbin construction required by this invention is a series of evenly spaced radial notches 70 formed in the end face of each flange 44 of the bobbin.

It is the purpose of the radial notches 70 to provide for a ratchet drive for the bobbin in one direction of rotation and to prevent retrograde motion of the bobbin during bobbin thread replenishment. Cooperating with the radial notches 70 in one bobbin flange is a bobbin driving pawl 71 keyed and secured fast on a drive rod 72 by a screw 73. The drive rod is endwise slidable in an axial bore 74 formed in the loop taker drive shaft 15 and a radial pin 75 set into the drive rod 72 protrudes outwardly through a slot 76 formed lengthwise in the loop taker drive shaft. The bobbin driving pawl 71 may be retracted into a cavity 77 formed in the shuttle driver 16 as shown in FIG. 1 or may be shifted out of the cavity into engagement with the bobbin flange 44 as shown in FIG. 2 by means of a control lever 78 fulcrumed at 79 beneath the bed 11. The control lever includes a handle 80 extending upwardly through an opening 81 in the bed for access by the machine operator. The control lever also is formed with a bifurcated extremity 82 each branch of which carries an inwardly extending pin 83 embraced by the annular groove 84 in a collar 85 slidable on the loop taker drive shaft. A coil spring 86 arranged in the loop taker shaft bore 74 bears against the drive rod 72 and biases the radial pin 75 towards the left as viewed in FIG. 1 against the collar 85. By manipulation of the handle 80, therefore, the pawl 71 may be shifted selectively into or out of driving relationship with the bobbin.

To prevent retrograde movement of the bobbin during the return oscillation of the driving pawl 71, an annular spring member 90 is inserted in the bobbin case between the bobbin case and the bobbin. The annular spring member 90 is provided with a pair of curved spring arms 91 and 92 which are bent laterally toward that side of the spring member 90 which faces the bobbin, i.e., toward the right as viewed in FIGS. 1, 2, and 3. The spring arms 91 and 92 differ not only as to their radial position but also in that the arm 91 is offset laterally to a greater degree. The spring arm 92 which is offset the least is disposed opposite the ratchet notches 70 in the bobbin flange, the spring arm 91 is not in registry with the notches 70. The spring member 90 is also formed with a peripheral tab 94 which is offset laterally in a direction opposite the spring arms 91 and 92 and which engages any one of a plurality of apertures 93 formed through the face of the bobbin case to prevent the spring 90 from turning. The apertures 93 may be associated with the bobbin case latch 37 as is conventional in the type of bobbin case hereinbefore described or if a different type of latch device is employed, apertures or recesses 93 may be formed in the bobbin case face for anchoring the spring 90.

Only when the spring arm 91 is deflected by shift of the bobbin to the left as viewed in FIG. 2 i.e., when the driving pawl

71 engages the bobbin to replenish thread, will the spring arm 92 engage the radial notches 70 in the bobbin flange and thus prevent retrograde movement of the bobbin.

When the bobbin driving pawl 71 is retracted as shown in FIG. 1 so that the parts occupy a position for sewing, the spring arm 91 of the spring member 90 will shift the bobbin slightly to the right and the spring arm 92 will become ineffective to prevent retrograde movement of the bobbin. The bobbin during sewing, therefore, will be free to turn and free to pay out bobbin thread to the stitches being formed.

When the bobbin driving pawl 71 is shifted into driving engagement with the bobbin as shown in FIG. 2, the spring arm 91 will be compressed laterally so that the retrograde preventing action of the spring arm 92 will become effective.

In operation, therefore, thread may be replenished on the bobbin 43 in place in the loop taker 27 when the operator of the sewing machine shifts the handle 80 to the right as viewed in FIG. 1 to render effective the ratchet drive for the bobbin. In addition, the operator need only grasp a loop of needle thread as it is being manipulated by the shuttle 27 and manually insert the needle thread into the slot 60 as described above. Subsequent operation of the sewing machine will thereafter cause the ratchet pawl 71 to drive the bobbin in increments in one direction of rotation. The needle thread being caught in one of the bobbin flange slots 65 and thus anchored to the bobbin, will be wound onto the bobbin hub 42. The lead of the needle thread into the bobbin will immediately be drawn to the extremity 61 of the thread slot 60 in the bobbin case skirt which as shown in FIGS. 1 and 2 is spaced centrally of the bobbin flanges 44. The resulting thread package wound on the bobbin will present an even distribution of thread on the hub 42 and the maximum length of thread may thus be wound on the bobbin.

As illustrated in FIG. 3, the needle aperture 22 is located on the left-hand side of shuttle bearing rib 31 so that the needle path through the aperture 22 will occur to the left of the thread engaging beak 32 of the shuttle. With this arrangement, with no work fabrics at the stitching point of the sewing machine the needle thread once manually inserted in the bobbin case slot 60 will no longer be presented to the shuttle beak 32 for loop seizure despite subsequent needle reciprocation during bobbin thread replenishment. When replenishment of bobbin thread has proceeded until a desired quantity has been wound on the bobbin, the operator can terminate winding by shifting the control handle 80 to the left as viewed in FIG. 1. When work fabrics are then placed at the stitching point of the sewing machine and the sewing machine needle is next lowered to penetrate the work fabrics, a needle thread loop will be presented to the shuttle beak 32 and this loop will be concatenated in a conventional fashion about the bobbin in the shuttle to form a lockstitch with the thread previously wound on the bobbin.

Having set forth the nature of this invention, what is claimed herein is:

We claim:

1. In a lockstitch sewing machine having an endwise reciprocating thread carrying needle, an oscillatory loop taker having a thread-carrying bobbin journaled therein, and an oscillating drive member for imparting movement to said loop taker for cooperation with said needle in the formation of lock stitches, mechanism for replenishing thread from said thread-carrying needle onto said bobbin in place in said loop taker comprising a bobbin driver carried for oscillation with said loop taker drive member, overrunning clutch means carried on said thread carrying bobbin and on said bobbin driver for drivingly coupling said bobbin with said bobbin driver in only one direction of oscillation of said bobbin driver, and means for selectively shifting said overrunning clutch means into and out of cooperative interrelation.

2. A bobbin thread replenishing mechanism for a sewing machine as set forth in claim 1, in which said overrunning clutch means comprises a first ratchet and pawl arrangement including a ratchet means formed on said bobbin and a spring

loaded pawl carried by said oscillating drive member and arranged for cooperation with said ratchet means.

3. A bobbin thread replenishing mechanism for a sewing machine as set forth in claim 1 in which said thread-carrying bobbin is journaled in a bobbin case which bobbin case is restrained from partaking of the oscillatory movement of the loop taker, and in which a retrograde overrunning clutch means is carried on said thread-carrying bobbin and on said bobbin case.

4. A bobbin thread-replenishing mechanism for a sewing machine as set forth in claim 2 in which said thread-carrying bobbin is journaled in a bobbin case which bobbin case is restrained from partaking of the oscillatory movement of the loop taker, and in which a second ratchet and pawl means is provided on said bobbin and said bobbin case for preventing retrograde movement of said bobbin during the other direction of oscillation of said bobbin driver.

5. A bobbin thread-replenishing mechanism as set forth in claim 4 in which said first and second ratchet means are both

carried on said bobbin and each ratchet means takes the form of similarly spaced series radial notches formed on a respective one of the bobbin flanges.

6. A bobbin thread-replenishing mechanism as set forth in claim 5 in which said second pawl means comprises an annular spring member adapted to be positioned between said bobbin case and said bobbin, said annular spring member including at least one spring arm laterally offset toward said bobbin case for engagement with abutment means formed on said bobbin case, and said annular spring including at least two spring arms laterally offset in different amounts toward said bobbin, only that one of said at last two spring arms which is offset the least being disposed for cooperative engagement with said ratchet means on said bobbin so that said second ratchet and pawl means will become effective to prevent retrograde movement of said bobbin only while the pawl of said first ratchet means is shifted into operative engagement with said bobbin.
